(Cl. D34—13)

To all whom it may concern:

Be it known that I, John Brzeski, a citizen of the United States of America, residing at Chicago, in the county of Cook and State of Illinois, have invented a new, original, and ornamental Design for a Pack of Game Cards, of which the following is a specification, reference being had to the accompanying drawings, forming part thereof.

Figures 1 through 11 are face views of the cards of one suit.

Figures 12 and 13 are face views of the first and last cards, respectively, of a second suit.

Figures 14 and 15 are face views of the first and last cards, respectively, of a third suit.

Figures 16 and 17 are face views of the first and last cards, respectively, of a fourth suit.

Figures 18 and 19 are face views of the first and last cards, respectively, of a fifth suit.

Figure 20 is a face view of a single card completing the pack.

The backs of the cards shown in the drawing are plain and unornamented.

The dominant features of my design are shown in solid lines in the drawing.

The medallions are shaded for color contrast.

Figs. 2 to 10 inclusive are representative of the face views of the intermediate cards of each suit, the total number of cards in the pack being 56.

I claim:

The ornamental design for a pack of game cards, as shown and described.
